E. SCHNEIDER.
MOTION PICTURE APPARATUS.
APPLICATION FILED AUG. 7, 1916.

1,242,605.

Patented Oct. 9, 1917.

Inventor
Eberhard Schneider
By his Attorney
Frank T. Schucker

UNITED STATES PATENT OFFICE.

EBERHARD SCHNEIDER, OF NEW YORK, N. Y.

MOTION-PICTURE APPARATUS.

Specification of Letters Patent.

Patented Oct. 9, 1917.

1,242,605.

Application filed August 7, 1916. Serial No. 113,477.

To all whom it may concern:

Be it known that I, EBERHARD SCHNEIDER, a citizen of the United States, and a resident of New York, in the county of New York and State of New York, have invented certain new and useful Improvements in Motion-Picture Apparatus, of which the following is a specification.

The invention relates to accessories to motion picture apparatus, such as cameras and projecting machines; and it has for its object to provide means to induce a circulation of air in the vicinity of said apparatus for the purpose of removing the static electricity with which the film becomes charged in rubbing over various supports, rollers and other portions of the apparatus, the undesirable results of which charge on the film are seen in the striations and lightning effects produced thereon.

The nature of the invention will be best understood when described in connection with the accompanying drawings, in which—

Figure 1 is a perspective view of a motion picture camera, as one embodiment of the invention.

Fig. 2 is a similar view with the door opened to display the mechanism.

Fig. 3 is a detail plan of the means for inducing the circulation of the air in the camera.

Similar characters of reference designate corresponding parts throughout the several views.

Referring to the drawings, 10 designates a suitable box, herein shown as of a camera type, carrying at its top the finder 11, and in front, a lens shade 12. At the side, a door 13 is provided, swinging on hinges 14 and carrying a portion of the film moving mechanism 15, which is driven by a crank handle 16 projecting through the said door 13 to advance the film 18, the said mechanism, however, forming no part of the present invention. The portion attached to the inside of the door 13 is provided with a key 19 at the shaft end to fit a corresponding slot 20 of the other portion, which is mounted in the box 10. On the inside of the door 13, moreover, there is secured a suitable device for inducing a circulation of the air or other fluid within or through the box and in the vicinity of the film and its advancing mechanism. The same is herein shown to consist of a short-cylinder 21 having a central shaft 22 and hub 23, from which latter

radiate vanes or blades 24, the same being inclined from the top to the bottom. On the shaft 22 is secured a pinion 25 to rotate the said fan by engaging an internal gear 26, as shown in Fig. 2. Said gear 26 is on the shaft 27 of a portion of the film moving mechanism driven by crank 16; and the velocity ratio between the same and pinion 25 is such as to rotate the latter at a sufficiently high speed to provide for a proper circulation of the air within or through the container 10. It will be understood that other blowing or suction apparatus could be employed for this purpose and that the same may be variously driven. The general arrangement is such that the current of air provided will remove the charge of static electricity which tends to accumulate, generally on the under or celluloid side of the film. The undesirable results obtained when no provision is made for doing away with the static electricity are thereby obviated and in a particularly simple manner.

I claim:

1. In a motion picture machine: a film, and film moving mechanism; means to support and guide said film through the machine; and means to induce a circulation of fluid in the vicinity of said guiding and supporting means for the purpose of removing from said film any static electricity with which it may have become charged through frictional engagement therewith.

2. In a motion picture machine: a film, and film moving mechanism; means to support and guide said film through the machine; and means driven by said mechanism to induce a circulation of air past said film and in the vicinity of said guiding and supporting means for the purpose of removing therefrom any static electricity with which it may have become charged through frictional engagement therewith.

3. In a motion picture machine: a film, and film moving mechanism; means to support and guide said film through the machine; and a fan driven by said film moving mechanism to induce a circulation of air in the vicinity of said guiding and supporting means for the purpose of removing from said film any static electricity with which it may have become charged through frictional engagement therewith.

4. In a motion picture camera: a film, and film moving mechanism; a box containing said mechanism and film; means to support

and guide said film through the machine; and a fan mounted within said box and adapted to be rotated by said film moving mechanism to induce a circulation of air past said film and in the vicinity of said guiding and supporting means for the purpose of removing from said film any static electricity with which it may have become charged through frictional engagement with said guiding and supporting means.

5. In a motion picture camera: a film, and film moving mechanism; a box containing

said mechanism and film and having a hinged door, a portion of the film moving mechanism being secured to the inside of the said door; a crank outside the box to rotate said film moving mechanism; and a fan carried by said door and connected to said film moving mechanism to be driven thereby when the said crank is rotated.

Signed at New York, in the county of New York and State of New York this 3rd day of August, A. D. 1916.

EBERHARD SCHNEIDER.
